UNITED STATES PATENT OFFICE.

FRANK C. NORCROSS AND JAMES MITCHELL, OF LORAIN, OHIO.

BLAST-FURNACE.

SPECIFICATION forming part of Letters Patent No. 700,549, dated May 20, 1902.

Application filed February 15, 1902. Serial No. 94,335. (No model.)

To all whom it may concern:

Be it known that we, FRANK C. NORCROSS and JAMES MITCHELL, citizens of the United States of America, and residents of Lorain, 5 in the county of Lorain and State of Ohio, have invented certain new and useful Improvements in Blast-Furnaces, of which the following is a specification.

This invention relates to ore-smelting furnaces, and has for its object to greatly facilitate and economize the operations and greatly increase the products of such furnaces.

Heretofore the dust from the stock ore has been allowed to go to waste and has required 15 additional facilities for disposing of it. Our invention is designed to prevent this loss and to enhance the quality and value of the products.

The invention consists in the introduction 20 of the dust into the furnace at points between the hearth and the stock-line in the upper part of the furnace by means of pipes in the sides and through the walls of the furnace or in connection with the blowpipes. The 25 dust is to be forcibly injected by any suitable means, as with a blower, steam, or electric power.

In the accompanying drawing, which illustrates our invention, the figure is a vertical 30 section of a blast-furnace.

A represents a smelting-furnace, which may be of any of the well-known forms and construction.

B B are the air-blast blowpipe-nozzles and 35 twyvers. b b are nipples on said blowpipes for the attachment of dust-pipes for the introduction of dust in conjunction with the air-blasts.

C C are pipes fixed in the walls of the furnace in such numbers and localities as may

be required between the stock-line and the hearth.

D is a dust-catching pipe connected with the pipes C C.

E is a blower connected by branches F F 45 with the pipe D opposite to the connections with the pipes C C. In said branches are provided cocks G G, by means of which the blower may be shut off from the furnace as desired and communication with the furnace controlled, so that any one or more of the 50 pipes may be used at a time.

The dust, which is now usually caught in a dust-catcher, may be conveyed to the pipes B B and C C and forcibly injected through 55 them into the furnace. By this means it is found that the dust can be quickly and safely put into the furnace, where it is instantly mingled with the contents, and thus avoid the liability and danger of being returned to 60 the dust-catcher by slipping of stock or explosion.

Having described our invention, what we claim is—

In combination with a blast-furnace, a dust-collecting pipe, a series of injecting-pipes inserted through the walls of the furnace, at intervals from top to bottom, and connected transversely with said dust-pipe, and means, substantially as described, connected to said 70 injection-pipes for forcibly injecting the dust into the furnace, substantially as and for the purpose set forth.

Signed by us at Cleveland, Ohio, this 11th day of February, 1902.

FRANK C. NORCROSS,
JAMES MITCHELL.
